Des. 214,333
Patented June 3, 1969

214,333

TRAY FOR CONDIMENTS DISPENSERS OR THE LIKE

James Baldwin Swett, Barrington, R.I., assignor to Dart
Industries, Inc., a corporation of Delaware

Filed July 3, 1968, Ser. No. 12,622

Term of patent 14 years

Int. Cl. D7—01

U.S. Cl. D44—7

FIG. 1

FIG. 2

FIG. 3

FIG. 4

FIG. 5

FIGURE 1 is a perspective view of a tray for condiment dispensers or the like showing my new design;

I claim:

The ornamental design for a tray for condiment dispensers or the like, substantially as shown.
